UNITED STATES PATENT OFFICE.

DAVID A. McCONNELL, OF KEARNEY, NEBRASKA.

THRESHING-MACHINE.

1,099,070.

Specification of Letters Patent.

Patented June 2, 1914.

Application filed January 22, 1913. Serial No. 743,634.

To all whom it may concern:

Be it known that I, DAVID A. McCONNELL, a citizen of the United States, residing at Kearney, in the county of Buffalo and State 5 of Nebraska, have invented new and useful Improvements in Threshing-Machines, of which the following is a specification.

This invention relates to threshing machines, and it has for its object to provide a 10 simple and improved construction whereby the interior of the threshing mechanism and particularly the concave is rendered conveniently accessible for repairs without necessity for first removing the cylinder.

15 A further object of the invention is to simplify and improve the construction of the concave with a view of rendering the toothed bars thereof conveniently detachable and replaceable in order that any injury 20 such as the breaking of a tooth may be quickly and conveniently repaired.

With these and other ends in view which will readily appear as the nature of the invention is better understood, the same consists in the improved construction and novel 25 arrangement and combination of parts which will be hereinafter fully described and particularly pointed out in the claims.

In the accompanying drawings has been 30 illustrated a simple and preferred form of the invention, it being, however, understood that no limitation is necessarily made to the precise structural details therein exhibited, but that changes, alterations and modifications 35 within the scope of the claims may be resorted to when desired.

In the drawings,—Figure 1 is a top plan view, showing the front portion of a threshing machine equipped with the improvement, the cylinder having been removed.

40 Fig. 2 is a longitudinal sectional view of the same, the cylinder having been shown in position and the concave being likewise in position for operation. Fig. 3 is a longitudinal sectional view showing the cylinder in 45 position and showing the front door removed, and showing also the concave dropped and one of the toothed bars in the act of being detached. Fig. 4 is a transverse

sectional view taken on the line 4—4 in Fig. 50 2. Fig. 5 is a side elevation. Fig. 6 is a perspective view of the concave frame detached.

Corresponding parts in the several figures are denoted by like characters of reference. 55

The throat of the threshing machine casing includes the side members 1, 1 which are extended forwardly of the main casing, a portion of which appears at 2, said side members being rounded on their undersides, 60 as indicated, so that the front portion of the throat will present the least possible obstruction to a person working beneath the same when performing needed repairs. This is in conformity with the construction 65 illustrated in Patent No. 1,038,926, granted to me on September 17, 1912. The cylinder 3 is supported for rotation on the side members 1, the customary cover for said cylinder being provided, as shown at 4. 70

5 is a feed board.

The concave frame is composed of side members 6 of arcuate shape, said side members being provided in their inner opposed faces with grooves 7 extending to the front 75 ends of the side members where said grooves are open for the admission of the bars 8 having the teeth 9, which latter are of conventional shape and are preferably detachably connected with the bars by means of 80 nuts 10 engaging the threaded shanks 11 of the teeth. The concave frame is pivotally supported on a rod 12 that extends transversely through the throat, said rod being provided with a wing nut 13 which may be 85 tightened against the proximate side member of the throat. The side members 6 of the concave frame are provided on their undersides with cam-shaped projections 14.

A rock shaft 15, which extends transversely through the throat of the machine, is supported for oscillation by the side members 1 beneath the concave frame, and said shaft is provided with a crank or offset 90 16 extending the entire distance between the 95 side members 1. Said crank or offset portion is adapted to engage and support the side members of the concave frame, being

in engagement with the shoulders 17 at the lower ends of the cams 14, as seen in Fig. 2. It is obvious that by rocking the shaft 15 to withdraw the crank from such engagement the concave frame will drop by gravity to the position indicated in Fig. 3. The rock shaft 15 has at one end a hand lever 18, whereby it may be manipulated, said lever being provided with a head 19 having a tooth or ratchet 20 adapted to be engaged by a pawl or dog 21, whereby it will be held securely in position to prevent accidental disengagement of the crank or offset portion 16 from the shoulders 19.

15 The side members 1 of the throat are connected together beneath the feed board 5 by a rod 22 having a wing nut 23. By tightening said wing nut, as well as the nut 13 on the rod 12, the side members 1 will be drawn together so as to clamp between them the concave casing, thereby materially assisting in supporting the latter in position for operation when, as is well known, it is subjected more or less to a strain of a 25 heavy nature. Much of the strain on the crank 16 and rock shaft 15 may thus be relieved.

A removable door or closure D for the front end of the throat of the machine is provided, said closure being in the nature of a curved plate having straight upper and lower edges and arcuate side edges, and said plate being provided on its concave face near the upper edge thereof with hooks 24, whereby it may be detachably supported on the rod 22, the lower end of said plate being loosely supported on the cross bar 25 at the front end of the main portion of the machine casing. This removable door or closure is described and claimed in the Letters Patent issued to me, as hereinbefore mentioned.

From the foregoing description, taken in connection with the drawings hereto annexed, the operation and advantages of this 45 invention will be readily understood.

The grain is fed over the feed board between the cylinder and the concave, and a considerable portion of the threshed grain will pass between the toothed bars of the 50 concave on to the curved closure member D over which it is discharged on to the customary conveyer. Access to the space between the concave and the cylinder for the purpose of repairing the concave or removing 55 material that may have become blocked or lodged between the cylinder and concave, or for other reasons, may be readily had by removing the closure D and actuating the rock shaft 15 to disengage the crank 16 from the shoulders of the cams 14, when the concave will drop by gravity to the position shown in Fig. 3. When the concave is in this position, the toothed bars 8 may be

readily slid out at the front end for the purpose of replacing teeth that may have been broken. To restore the concave to its initial position, the rock shaft is rotated to cause the crank 16 to exert a lifting action on the undersides of the cams 14 until the crank slips beneath the shoulders 17 at the lower ends of said cams, after which the pawl 21 may be placed in engagement with the ratchet 20, thereby locking the rock shaft against displacement. By tightening the wing nuts on the rods 12 and 22 the concave will be retained with additional security, as will be readily understood.

Having thus described the invention, what is claimed as new, is:—

1. A threshing machine casing including a throat having side members, a concave including curved side members pivoted on the rod and having grooves in their opposed faces, said grooves being open at their front ends, and tooth carrying bars slidably engaging the grooves, a rock shaft supported on the side members of the throat and having a crank extending between said side members, and cams on the undersides of the side members of the concave engaged by said crank, and means for actuating the rock shaft to throw the crank out of the path of the cams to permit the concave to swing to a position where the tooth carrying bars may be removed.

2. A threshing machine casing including a throat having side members, a concave, a rod on which said concave is pivotally supported at the rear end thereof, a rod connecting the side members of the casing in advance of the concave, and tightening nuts on said rods whereby the side members of the casing may be clamped on the concave to hold the latter frictionally against displacement.

3. A threshing machine casing including a throat having side members, a concave, a rod on which said concave is pivotally supported at the rear end thereof, a rod connecting the side members of the casing in advance of the concave, and tightening nuts on said rods whereby the side members of the casing may be clamped on the concave to hold the latter frictionally against displacement, in combination with means for positively supporting the concave in position for operation including a rock shaft having a crank, cams on the concave engaged by said crank, and means for actuating the rock shaft to move the crank out of the path of the concave.

4. A threshing machine casing including a throat having a side and a detachable front closure member, a concave including grooved side members and tooth carrying bars slidably and detachably engaging said

side members, a rod on which the concave is pivotally supported, a supporting rod for the detachable front closure member, said rods having threaded ends extending through the side members of the casing, and nuts on the threaded rods for compressing the side members of the casing upon the side members of the concave and the latter upon the

tooth carrying bars to maintain the parts in position frictionally.

In testimony whereof I affix my signature in presence of two witnesses.

DAVID A. McCONNELL.
